SHOE AND INSOLE THEREFOR

Harold Warren, Swampscott, Mass., assignor to
 United Shoe Machinery Corporation, Borough
 of Flemington, N. J., a corporation of New
 Jersey

Application November 5, 1937, Serial No. 173,009

3 Claims. (Cl. 36—17)

This invention relates to improvements in shoes and insoles therefor.

In a welt shoe the sewing rib of the insole tends to stiffen the insole so as to render the shoe bottom incapable of flexing as freely as is required to accommodate the bending movements of the foot.

It is one of the objects of the present invention to insure a higher degree of flexibility in the bottoms of welt shoes.

With this object in view the invention in one aspect consists in a welt shoe comprising an insole and having an upstanding integral sewing rib interrupted at the ball of the shoe by openings extending substantial distances lengthwise of said rib and having a layer of reinforcing material covering the surface of the insole within said rib, said layer having a marginal portion overlying the inner side of said rib and bridging said openings, an upper and a welt secured to said rib by means of an inseam, and an outsole secured to said welt, said inseam extending through said marginal portion of the reinforcing layer where it overlies said rib and also through said marginal portion where said rib openings are located.

Invention is also to be recognized as residing in an insole of novel construction, the insole having an upstanding rib portion extending along one lateral margin of its shank part and another upstanding rib portion extending along the corresponding lateral margin of its forepart, the rib portions being separated at the ball of the insole by a gap of substantial extent lengthwise of the rib portions and a layer of reinforcing material secured to that portion of the insole surface which is located at the inner sides of the rib portions, said layer having an upstanding margin, portions of which are secured to the rib portions and another portion of which bridges said gap.

The invention will be explained with reference to the accompanying drawing, in which

Fig. 1 is a perspective view of an insole prepared in accordance with the present invention;

Fig. 2 is a fragmentary perspective view of the insole illustrating the performance of certain preparatory operations thereon;

Fig. 3 is a fragmentary cross-sectional view of a shoe in process of construction, showing an upper secured in overlasted position upon an insole such as that shown in Fig. 1;

Fig. 4 is a perspective view of the shoe as it appears after the inseaming and inseam trimming operations have been performed;

Fig. 5 is a fragmentary cross-sectional view of the shoe taken along the line V—V of Fig. 4;

Fig. 6 is a fragmentary perspective view of a welt strip used in the making of the shoe;

Fig. 7 is a fragmentary cross-sectional view of the shoe taken along the line VII—VII of Fig. 4;

Fig. 8 is a cross-sectional view of the finished shoe;

Fig. 9 is a fragmentary cross-sectional view of a shoe in course of construction illustrating an alternative method of securing the welt to the upper in the ball portion of the shoe; and

Fig. 10 is a cross-sectional view of the shoe shown in Fig. 9, illustrating a further step in the process of making the shoe.

In making my improved shoe, an insole 16 is channeled in a well-known manner to provide inner and outer marginal channels the lips or flaps 18 and 20 of which are raised and cemented together to form an upstanding two-ply lasting 22 and sewing rib 22, the rib as initially formed extending continuously around the forepart and along both lateral margins of the shank portion of the insole. In order that the shoe in which the insole is to be incorporated shall be better adapted to accommodate the bending movements of the foot, portions of the rib 22 are removed in the forepart of the insole so as to render the latter capable of bending or flexing more freely.

As shown in Fig. 1, a section of substantial length and of full rib thickness has been removed from the insole rib 22 at each side of the forepart in the ball portion of the insole thus providing openings or gaps 24 in the rib and enabling the insole to bend more easily in the vicinity of the ball line. The length and locations of the openings 24 in the rib may, however, be varied to

vary the extent of the area of increased flexibility and to control the location of the break line in the shoe upper and in the shoe bottom as may be found desirable. The openings 24 may be formed in the rib 22 by any suitable means,

for example, by the use of a hand knife 26, the knife being manipulated at each lateral margin of the insole to make spaced incisions 28 in the rib, perpendicular to the face of the insole, and also to make a cut extending lengthwise of the rib along the base or root of the latter and intersecting the incisions 28 so as to remove the rib entirely and leave no upstanding elements in

the ball portion of the insole. After the openings 24 have been formed in the rib the insole is reinforced by means of a layer 34 of canvas or the like which is cut to correspond to the insole edge contour and is cemented to the ribbed

side of the insole, the marginal portions of the reinforcing layer being cemented to the inner side of the upturned rib. In the localities where the openings 24 are formed slits 36 are cut in the 5 marginal portions of the layer 34, the slits being spaced apart so as to form lasting tabs 38 between them and these tabs are cemented to the feather of the insole so as to provide surfaces thereon of a character suitable for the reception 10 of pyroxylin cement. A reinforced insole is thus provided which, in addition to having all the advantages of the well-known Economy insole, has a maximum amount of flexibility in the ball portion of its forepart (inasmuch as the stiffening effect of the sewing rib has been eliminated in that locality) and which is also especially adapted, at the margins of its ball portion for the reception of cement by means of which the upper of a shoe may be permanently held in overlasted position.

In using the above-described insole in the manufacture of a shoe the insole is assembled with an upper 40 and an upper lining 42 upon a last 44. The upper materials are pulled over 25 and lasted in the usual way and are secured in overlasted position upon the feather 45 of the insole. As herein shown, the overlasted margin of the upper is thus secured in position where the sewing rib is left intact by means of staples 30 46 (Fig. 3) which are driven through the rib while in the localities where the rib has been cut away the upper is secured to the insole by means of pyroxylin or other suitable cement, the lining 42 being cemented to the canvas reinforcing layer 34 and the upper 40 being secured by cement to the overlasted portion of the lining, as indicated 35 at 48 in Fig. 4. The overlasted portions 48 of the upper are then roughed, as indicated at 50, to prepare them for the cement attachment of 40 the welt thereto, as will be explained later. Thereafter, the overlasted margins of the upper materials, together with a welt 52, are secured to the rib 22 by inseam stitches 54. The inseam stitching operation may proceed continuously 45 around the shoe bottom, the stitches 54, however, passing only through the welt, as indicated in Fig. 5, in the localities where the rib has been cut away and where the upper materials are to be secured by cement to the surface of the 50 insole. The usual inseam trimming operation may now be performed and suitable filling material applied to the portion of the shoe bottom at the inner side of the sewing rib. Thereafter, an outsole 58 is laid and attached as by outseam 55 stitches 60 (Fig. 8) to the welt 52 although the outsole may be attached to the shoe by means of cement if desired. In the areas where the rib 22 has been cut away and where the inseam stitches do not pass through the upper, the upper and the welt may now be secured together by 60 means of pyroxylin or other suitable cement. Advantageously, the cement may be applied just prior to the leveling of the shoe bottom so that the leveling pressure will cause the cemented parts to become firmly bonded together. To assist in securing a satisfactory cement bond between the welt and the upper in these localities it is desirable to employ a welt the inner marginal portions of which have been pre-roughed at the 65 side which is to be attached to the upper, as indicated at 62 in Fig. 6. The cement may be introduced between the welt and the upper from the outside of the shoe after the outsole has been attached although, if desired, it may be introduced before the outsole is laid and before the 70

bottom filler is applied in which case the cemented parts may be held under pressure against the bottom of the last during the setting of the cement by the use of any suitable pressure applying means.

In attaching the welt to the upper at the ball of the shoe where the sewing rib is cut away, the inseam stitches 54 may be passed through the welt and the upper materials and through the margin of the reinforcing layer 34, as shown in 10 Fig. 9, the margin of the layer 34 being upturned, as indicated where the openings in the rib are located. In accordance with this procedure the upper and lining need not be secured to the insole with cement during the lasting operation, 15 in the localities where the rib is cut away, inasmuch as the lasting staples 46 which penetrate the rib 22 at opposite sides of the openings 24 will serve to hold in overlasted position the portions of the upper at the openings 24 and the 20 inseam stitches securing the upper to the reinforcing layer 34 will permanently secure the upper to the insole.

While in Fig. 9 I have shown the margin of 25 the reinforcing layer 34 upturned where the opening in the sewing rib is located, it may be laid flat upon and cemented to the insole feather in that locality, as hereinbefore described, and as shown in Fig. 10, in which case the inseam 30 stitches 54 will extend only through the welt and the upper materials. In either case, after the inseam stitching operation has been completed the upper margin which extends inwardly beyond the inseam may be laid flat against the insole 35 and secured thereto by cement as indicated at 64 in Fig. 10.

In a welt shoe made as above described there is no sewing rib with portions of the welt and the upper tightly secured thereto by inseam 40 stitches at the ball portion of the shoe bottom to stiffen the insole and thus to interfere with the flexing of the shoe bottom. The upper materials in this locality are overlasted flat upon the insole as in a McKay-sewed shoe but there 45 is no through-and-through stitching securing together the upper and the inner and outer soles. Consequently the shoe, although having the well-known advantages of a welt shoe, is more flexible than either a shoe of the usual welt construction 50 or a McKay-sewed shoe. Moreover, the construction of the shoe in the ball portion where the maximum amount of bending takes place is such that no structural weakness is developed 55 as a result of the removal of the sewing rib in the ball portion of the shoe since in that region the upper is very firmly attached by cement to the reinforcing layer of the insole and the welt is firmly secured to the upper either by cement or by the inseam stitches.

Having described my invention, what I claim 60 as new and desire to secure by Letters Patent of the United States is:

1. A welt shoe comprising an insole having an 65 upstanding integral sewing rib interrupted at the ball of the shoe by openings extending substantial distances lengthwise of said rib and having a layer of reinforcing material covering the surface of the insole within said rib, said layer having a marginal portion overlying the 70 inner side of said rib and bridging said openings, an upper and a welt secured to said rib by means of an inseam, and an outsole secured to said welt, said inseam extending through said marginal portion of the reinforcing layer where it overlies 75

said rib and also where said rib openings are located.

2. A welt shoe comprising an insole having an upturned integral sewing rib interrupted at the ball of the shoe by an opening extending a substantial distance lengthwise of said rib, a piece of fabric secured to the ribbed side of said insole and having an upturned portion opposite said rib opening, an upper and a welt secured by means of an inseam to said rib, said inseam securing said upper and said welt to the upturned portions of said piece of fabric where said rib opening is located, and an outsole secured to said welt.

3. An insole having an upstanding integral rib portion extending along one lateral margin of its shank part and another upstanding integral rib portion extending along the corresponding lateral margin of its forepart, said rib portions being separated at the ball of the insole by a gap of substantial extent lengthwise of the rib portions, and a layer of reinforcing fabric secured to that portion of the insole surface which is located at the inner sides of said rib portions, said layer having an upstanding margin, portions of which are secured to said rib portions and another portion of which bridges said gap.

HAROLD WARREN.
